CLAIM

The ornamental design for an encapsulated conduits having jacket with sections of reduced material, as shown and described.

DESCRIPTION

FIG. 1 is a side perspective view of an encapsulated conduit having jacket with sections of reduced material of the present invention.

FIG. 2 is a first end view thereof.

FIG. 3 is a second end view thereof.

FIG. 4 is an overhead view thereof.

FIG. 5 is a bottom view thereof.

FIG. 6 is a first side view thereof; and,

FIG. 7 is a second side view thereof.

The broken line showing of a break in the middle of the design in FIGS. 1 and 4-7 is included for the purpose of illustrating indeterminate length and forms no part of the claimed design.

1 Claim, 4 Drawing Sheets
